UNITED STATES PATENT OFFICE.

WILLARD C. WETMORE, OF UPPER MONTCLAIR, NEW JERSEY.

HAT-COVERING.

1,083,344.

Specification of Letters Patent.

Patented Jan. 6, 1914.

Application filed May 24, 1911, Serial No. 629,147. Renewed May 28, 1913. Serial No. 770,450.

To all whom it may concern:

Be it known that I, WILLARD C. WETMORE, a citizen of the United States, residing at Upper Montclair, in the county of Essex 5 and State of New Jersey, have invented certain new and useful Improvements in Hat-Coverings, of which the following is a full, clear, and exact description.

This invention relates to preservative coverings for straw hats, and the like, whereby protection may be afforded for such articles from inclement weather.

I am aware that attempts have been made to provide protective coverings for hats, but 15 all such coverings have, to the best of my knowledge, been unsightly in appearance, and are indeed of such character that but few persons can be induced to wear the same.

20 One of the objects of my invention therefore is to provide a covering of the type in question which shall conform to the outline of, for example, a straw hat, and which may be made of such materials that when 25 in place upon the hat, the covering will not be objectionably noticeable.

A further object of my invention is to so 30 form my protective covering as to adapt it to fit hats of various sizes, various widths of brim, and heights of crown.

I further aim to provide a device of this 35 character which shall be adaptable for use with either stiff brimmed hats, or with hats the brims of which are moderately flexible; the device sufficiently conforming itself to 40 the shape of such a flexible hat as substantially not to distort the latter.

I further aim while providing a device 45 possessed of these desirable characteristics, to form the same of such light and highly flexible material that the covering may be readily rolled up, or folded, and placed in the pocket of the user, and when so disposed, the said covering is of such small bulk as 50 not to materially bulge the pocket in which it reposes.

These and other objects of my invention 55 will be hereinafter referred to and more particularly pointed out in the claim appended hereto.

In the drawings which form a part hereof and in which like reference characters 60 designate like parts throughout the several views: Figure 1 shows a stiff brimmed straw hat with my covering applied thereto, the

hat and covering being partly broken away in order to better illustrate the construction of the covering. Fig. 2 is a fragmentary vertical section taken substantially on the median line of the covering in question. 60

Referring to Fig. 1, the straw hat may be of the usual stiff brimmed type, as herein exemplified, and consists of the crown 1 and the brim 2, the hat being provided with the usual sweat band 3, if desired. Over the 65 outside of the hat is the protective covering broadly designated 4, which consists in this exemplification of my invention of a crown proper 5, preferably formed of thin and highly oiled silk, rubber treated linen, or the like, which may be, if desired, and in fact, preferably is, of a yellow color. Secured to this crown is a flat and preferably broad band 6 of sheet rubber or the like, the essential characteristic of this band being its 70 elasticity. The band in question may be formed of that class of rubber sheeting known as dam rubber. The protective crown 5 may be secured to this band by a line of stitching 7, or the like and the jointure may be cemented in addition. In the form of device illustrated, the crown portion overlaps the upper edge of the band. Correspondingly secured to the lower edge 75 of this band as at 8 is the brim covering portion of the device, which is adapted to flare abruptly away from the lower edge of the band as shown in Fig. 1, in order to conform to the usual flat brim of a hat of the 80 type in question. This brim forming portion, designated 9, is preferably formed of the same material as the crown. The characteristic common to both of these parts being their lack of elasticity. The free edge 85 of the brim cover 9 is folded over as at 10, the folded edge being secured to the adjacent portion of the brim cover by a line of stitching 11, or in any other suitable manner. Through the fold or annular pocket 90 thus formed extends a puckering cord 12, preferably of elastic material such as linen or cotton covered rubber cord, or the like, which holds the brim cover under proper tension when the latter is disposed around 100 the brim of the hat.

By reason of the provision of the elastic band 6, the protective covering as a whole is adapted to neatly and snugly fit substantially any straw hat of normal size to which 110

the covering may be applied. If the diameter of the crown be of relative large size, the band is stretched lengthwise to conform thereto, and if the crown be relatively 5 high the band is adapted to stretch in the direction of its width. The diameter of the crown portion 5 is preferably made sufficiently large to permit of its edge overlapping the edge of any normally sized hat to 10 which it may be applied in the manner shown in Fig. 1. Obviously if the hat crown be of small diameter this overlapping will be greater than in the case of hats having crowns of large diameter, but the flexibility 15 of the material of which this crown is composed admirably adapts itself to this purpose; the rubber band holding the oiled silk or like material snugly down over the crown of the hat so as to closely conform thereto. 20 The brim covering portion is correspondingly held flat if the hat brim be a stiff one, since the line of jointure of the elastic band 6 to the said brim covering portion will usually be disposed around the line of jointure 25 of the hat brim and its crown; this disposition of the covering parts being possible by reason of the fact that the brim covering portion is inelastic, and the only tension placed thereupon being due to the action of 30 the light elastic cord 12, which as will be observed is disposed upon the under side of the brim so that owing to the bend of the material over the edge of the brim, no material tendency is exerted by this cord to pull 35 the line of jointure 8 out of position. Then too the gripping action of the broad elastic band 6 tends to hold all parts of the latter in place, so that even when under moderate tension, as when placed upon a relatively 40 high crown and stretched in order to cover the same, the line 8 may be disposed substantially at the line of jointure of the brim in the manner aforesaid, and will there remain. If the rubber band be of black rubber 45 and the oiled silk be yellow in color, at a short distance the covering, as a whole, is practically indistinguishable from the usual straw hat.

Even when placed upon a hat, the brim 50 of which is relatively flexible, my protective covering does not objectionably distort this brim and the covering itself is, if constructed

of the materials above described, not at all unsightly.

I am aware that attempts have been made 55 to provide coverings for straw hats, but to the best of my knowledge these coverings have been made throughout of elastic material by reason of which the same cannot conveniently be conformed properly to the 60 hat; such coverings further, owing to the cost of rubber and like materials, being relatively expensive; whereas the present covering is decidedly inexpensive, the amount of 65 rubber used being small.

The rubber band in question may have the 70 ends thereof conveniently joined together in any suitable manner as at 13, but I prefer to cement the same with rubber cement or the like, which cement may also be used in 75 securing the oiled silk or like material to the rubber. It is obvious also that the elastic pucker cord 12 permits the device to be affixed to hats having brims of various widths.

When not in use the device may be conveniently carried in a pocket or any other receptacle and occupies but little space. It hence possesses many desirable characteristics, is exceedingly simple in construction 80 and possesses characteristics that have not heretofore been in evidence in devices of this character.

Having thus described my invention, I 85 claim:

As a new article of manufacture, a hat covering comprising a broad annular band of elastic material adapted to tightly embrace and cover the sides of the crown of the hat, an inelastic flexible portion secured 90 to the upper edge of said band and adapted to cover the top of the hat, an inelastic flexible portion secured to the lower edge of said band, the free edge of the latter portion being adapted to be folded over the edge of the hat brim, and means for contracting said 95 free edge, as and for the purpose set forth.

In witness whereof, I subscribe my signature, in the presence of two witnesses.

WILLARD C. WETMORE.
